GARAGE DOOR

William D. Ferris, Sterling, Ill., assignor to Frantz Manufacturing Co., Sterling, Ill., a corporation of Illinois

Application January 22, 1942, Serial No. 427,700

8 Claims.

(Cl. 20—19)

This invention relates to overhead doors and particularly to overhead doors of the rigid one-piece type, the upper ends of which are adapted to be guided along a substantially horizontal track disposed in more or less horizontal position adjacent the top of the door frame and wherein lever means pivoted to the door and to a fixed support located to the rear of the door frame is provided, so that when the door is closed it is disposed in a substantially vertical position with respect to the door frame and when open is in a substantially horizontal overhead position with respect to the door frame.

The object of the invention is to provide an overhead door construction including a counterbalanced door adapted to move from a substantially vertically closed position to an open substantially overhead horizontal position wherein there is provided means operative during the movements of the door for controlling the effective action of the counterbalancing means thereon in accordance with predetermined empirically selected values throughout the range of travel of the door, whereby empirically to control the operating forces on the door throughout its range of travel.

Among other objects of the present invention is to provide in association with the foregoing, spring power means including a spring and an elongated flexible member having one end connected to the door and the opposite end to a fixed support and to provide in association therewith a lever having one end pivoted to the bottom of the door and having its other end provided with means whereby the lever is pivotally mounted on a fixed support in such a manner that the pivotal point may shift along the length of the lever in a selected predetermined manner during the opening and closing movements of the door, whereby to provide controlled variant, opening and closing movements of the door; to provide in association with a door of the foregoing characteristics, cam means of a selected contour for controlling the distance from the inner end of the lever, of the shiftable axis about which the lever swings during the opening and closing movements of the door; to provide a cam means in association with a slotted lever and a shifting pivotal point for the lever in association with the cam means whereby to provide adjustments to suit variable spring tensions and to care for slight variations in weight of the door; to provide a device of the foregoing character which will also provide a positive stop for the full open position of the door; to provide these and

other objects of the invention as will be apparent from a perusal of the following specification when taken in connection with the accompanying drawings, wherein:

5 Figure 1 is a vertical sectional view taken on the line 1—1 of Figure 4.

Figure 2 is a perspective view of the cam plate.

Figure 3 is a detail plan section taken on the line 3—3 of Figure 1.

10 Figure 4 is a vertical cross sectional view of the door in closed position, taken on the line 4—4 of Figure 1.

Figure 5 is a similar view showing the door in open or overhead position.

15 Figure 6 is a detail plan sectional view taken on the line 6—6 of Figure 4.

Figures 7 to 11, inclusive, are vertical cross sectional views of the door in different positions of operation.

20 Referring now to the drawings in detail, the invention is illustrated in connection with a structure 2 having a door frame 4 providing an opening adapted to be closed by a door 6, which in closed position is substantially vertical, as shown in Figure 4, and which in open position is substantially horizontal, as shown in Figure 5. The door is of the one-piece rigid type and is preferably provided with a bracket 8 carrying a roller 10 at the upper corners of the door, which rollers are adapted to roll in tracks 12 extending within the structure at the top thereof and being substantially horizontal more or less, or slightly rearwardly inclined.

25 At its lower end the door is provided with a bracket 14, to which is pivoted as at 16, the outer end of a lever 18. This lever is adapted to have a shifting pivotal connection with a fixed support and means in association therewith are provided in the form of a cam for causing a predetermined, preselected shift of the pivotal axis of said lever in order to provide variant controlled opening and closing movements of the door, and for providing further a positive stop for the full open position of the door.

30 35 For this purpose the inner end of the lever is provided near its end with an elongated slot 20 adapted to receive a pin 22 mounted fixedly on a bracket 24. The inner end of this lever 18 carries a pin 26 provided with a head 28 and a threaded shank 30 and a nut 32. The pin is adapted to ride in a slot 34 formed on the flange 36 of the bracket 24, said bracket 24 having a flange 38 attached as by bolts 40 to the main vertical frame of the door.

40 45 It will be seen from the consecutive figures that

due to the urge of the spring mechanism herein-after described, the inner end of the lever 18 through the agency of the slot 20 may shift relatively to the fixed pin 22, such shifting movement being definitely controlled in all positions of the door by means of the fixed cam slot 34. This is very clearly shown in Figures 7 to 11, inclusive.

In cooperation with the foregoing structure, means is provided for counterbalancing the door in its opening and closing movements and in addition for giving the door an initial, automatic, opening movement.

This mechanism comprises a coil spring 42 having one end anchored as at 44 to a bracket 46 mounted on the rear face of the door 6. The opposite end of the spring is connected to an elongated flexible member preferably in the form of a cable 48, which passes around a sheave 50, preferably rotatable on the pin 16 on which the outer end of the lever 18 is pivoted. This cable 48 is anchored at its upper end as at 52 to a fixed support which in the present instance is a pin or any other anchorage on the door frame 4. Hence, this anchorage 52 is disposed to the rear of the door in the closed position of the door.

The spring 42 is the type having initial tension built and wound into it and the spring is arranged so that when the door is in completely open position the spring will tend to maintain a tension on the lever 18, whereby to hold the door completely open and to prevent it from rebounding when adjusted properly. In addition, this initial tension which is wound in the spring acts immediately to lift the door upwardly when the latching mechanism is released.

As before stated, the contour of the cam slot 34 may be varied to accomplish various controlled opening and closing movements of the door, depending upon the type of cam slot selected. The present invention includes the provision of a cam slot designed to change the effective length of the lever from its fixed pivotal axis 22 to its outer pivotal axis 16, where it is connected to the lower portion of the door.

In the fully closed position of the door, as shown in Figure 7, the pin 26 will be at the upper end of the cam slot 34 and the fixed pivotal pin 22 forming the pivotal axis about which the lever 18 swings, but located at the extreme outer end of the cam slot 20, in which position the minimum effective length of the lever is being utilized in association with the spring 42 and the cable 48. In this position, shown in Figure 7, the distance A, as shown by the arrows, is at a minimum. This line A is at right angles to line X which bisects the line of the spring 42 and its cable 48 and extends to the pivotal axis 22. This means that the spring will exert a relatively smaller force for opening the door the instant that the door latch is released.

The cam slot 34 provided in the plate 24 may be shaped in accordance with any desired curve or shape to thereby impart to the lever 18 the desired effective length at each and all positions within the range of travel of the door and the lever. In short, the cam track may be cut in accordance with empirically selected values thereby to impart empirically selected lever arm lengths to the lever 18 at each and all positions within its range of travel. It is, of course, understood that any desired shape of cam slot 34 may be designed to produce any desired effect on the opening and closing movements of the door.

The shape of the slot 34 selected is purely for illustrative purposes.

The contour of the cam slot 34 is designed so that in response to the urge of the spring 42, as the pin 26 moves along the slot 34, the distance A increases. This is due to the fact that the cam slot will cause the innermost end of the lever through the instrumentality of the pin 26 to be shifted toward the fixed pivotal axis pin 22 so that the slot 20 of the lever will permit the lever 18 as a whole to shift bodily to the left as shown in Figure 9.

This movement will serve to increase the effective length of the lever 18 from the point 22 to the point 16, which in conjunction with the force of the spring 42 and the cable 48, will tend to exert a constantly and progressively increasing upward force to accelerate the opening movement of the door. This accelerated movement will continue until the cam slot 34 reaches a point such as shown in Figure 10 where the pin 26 has reached such a position in the cam slot that the distance A is at its maximum.

From the position shown in Figure 10 the pin 26 will move in the cam slot to the position shown in Figure 11, which added movement progressively increases the distance or torque arm A cooperating with the decreasing force of application of the spring 42 to thereby impart the desired decreasing torque to the door as it approaches its fully open position.

Thus, during the completion of its full open movement the door will tend to slow down the predetermined desired amount until the final complete open position is reached, at which time any further movement is checked by the contact of the pin 26 with the adjacent end of the cam slot 34. At this time it will be noted that the pivot pin 22 will be at the opposite end of the slot 20 of the lever 18.

It will be appreciated that the present construction, through utilization of the various shaped cam slots 34, provides in each selected cam slot a controlled speed and movement of the door. In the present instance, the initial urge of the spring of the door will be relatively slow but will act positively to open the door instantly the door is unlocked without any preliminary urge to the door, and thereafter the speed of the opening of the door will accelerate to a predetermined point and will then tend to slow down in the speed of opening to the complete open position of the door.

Having thus described my invention, what I claim as new and desire to secure by Letters Patent is as follows:

1. An overhead door construction comprising a frame having an opening to be closed, a door adapted to be moved from a substantially vertical position closing said opening to an open substantially horizontal position adjacent the upper part of said opening, lever means pivoted to the door, means forming a fixed pivot for said lever, counterbalancing means for the door, means forming a shiftable pivotal connection between said lever and said fixed pivot, and cam means for controlling the shifting of said pivot during the opening and closing movements of the door.

2. An overhead door construction comprising a frame having an opening to be closed, a rigid door adapted to be moved from a substantially vertical position closing said opening to an open substantially horizontal position adjacent the upper part of said opening, lever means pivoted

to the door and to a fixed pivot for controlling the movements of the door, counterbalancing means for the door comprising a spring and a connected elongated flexible member, said counterbalancing means being disposed entirely behind the door when the latter is in closed position and being connected to the door and to a fixed support, said lever being shiftable lengthwise relative to its fixed pivot, and means for progressively controlling the lengthwise relative shifting movement of said lever relative to its fixed pivot during the movements of the door.

3. An overhead door construction comprising a frame having an opening to be closed, a door adapted to be moved from a substantially vertical position closing said opening to an open substantially horizontal position adjacent the upper part of said opening, lever means pivoted to the door and to a fixed support for controlling the movements of the door, counterbalancing means for the door, said lever having a slot passing about the pivotal axis of said lever, whereby to permit said lever to shift longitudinally relative to the pivotal axis of said lever, and cam means controlling such movement of the lever relative to its pivotal axis.

4. An overhead door construction comprising a frame having an opening to be closed, a rigid door adapted to be moved from a substantially vertical position closing said opening to an open substantially horizontal position adjacent the upper part of said opening, a lever having one end pivoted to the door, the opposite end of said lever having an elongated slot, means providing a fixed support having a fixed pin adapted to shift along the slot of said lever, a cam and means on the rear end of said lever adapted to engage the cam to control the relative movement of the pin in said slot of the lever, and counterbalancing spring means comprising a spring and a connected elongated flexible member for controlling the movements of the door, said counterbalancing means being connected to the door and to a fixed support.

5. In combination with a structure having an opening, a rigid door therefor having a vertical closed position and a more or less horizontal open position, a single lever having one end connected to said door, means forming a fixed pivot about which the lever is adapted to swing, counterbalancing means for the door, means disposed at a plurality of points along the length of said oppo-

site end portion of the lever, about which said lever is adapted to swing about said fixed pivot, and means for selectively controlling at which point of said plurality of points said lever will swing about its fixed pivot during any particular position of the door.

6. In combination with a structure having an opening, a door therefor having a vertical closed position and a more or less horizontal open position, means providing a fixed support, a fixed pivot pin thereon, a lever having one end pivotally connected to a lower portion of the door, the opposite end of said lever having an elongated slot extending lengthwise thereof, along which said fixed axis is adapted to move, said end of said lever adjacent said slot being provided with a pin, a fixed cam plate adjacent the inner portion of said lever, said plate having a cam slot along which said pin is adapted to ride, and counterbalancing means for said door.

7. In an overhead door construction of the type wherein the upper end of the door is slidably engaged in substantially horizontal tracks and the lower end thereof is pivotally connected to a pair of supporting arms, each pivotally mounted on stationary supports located at opposite sides of the door opening and substantially midway between the top and bottom of said opening, counterbalancing means for facilitating the opening of said door, said pair of supporting arms and their pivotal mounting including an elongated slot and pin connection to permit said arms and the pivotal mountings to shift relatively in a direction lengthwise of the arms and means for effecting a predetermined controlled relative shifting movement of said pins and said arms during the opening movement of said door.

8. In combination with a frame providing an opening, a rigid one-piece door therefor adapted in vertical position to close said opening and adapted to lie substantially horizontal in its open position, means forming a fixed pivot, a one piece lever pivoted to said door and to said fixed pivot for imparting a shifting movement to said door from said vertical position to said horizontal position, counterbalancing means for said door, and means operative during the swinging movement of said door for changing the distance along the lever between the point of pivotal connection of the lever to the door and the point of pivotal connection of the lever to its fixed pivot.

WILLIAM D. FERRIS.
